UNITED STATES PATENT OFFICE.

WARREN ALLISEN CROCKETT AND JUDSON NOELL HATCHER, OF AMERICUS,
MISSOURI.

DEVICE FOR COUNTING STAMPS.

SPECIFICATION forming part of Letters Patent No. 414,142, dated October 29, 1889.

Application filed May 11, 1889. Serial No. 310,445. (No model.)

To all whom it may concern:

Be it known that we, WARREN ALLISEN CROCKETT and JUDSON NOELL HATCHER, citizens of the United States, and residents of 5 Americus, in the county of Montgomery and State of Missouri, have invented certain new and useful Improvements in Devices for Counting Stamps; and we do declare the following to be a full, clear, and exact description 10 of the invention, such as will enable others skilled in the art to which it appertains to make and use the same, reference being had to the accompanying drawings, and to letters or figures of reference marked thereon, which 15 form a part of this specification.

Figure 1 is a face or front view of our invention, and Fig. 2 is a similar view with the dial removed.

This invention relates to an improvement 20 in devices especially adapted for keeping account of the sale of postage-stamps; and to this end the nature of the invention consists of the novel combination of parts and their construction, as will fully appear from the following description and accompanying illustration.

In carrying out our invention we employ a case or closure A, which is of metal, and within it is arranged a metallic tooth-wheel or 30 ratchet B, whose shaft *a* is supported at one end in a central aperture in a bracket *b*, secured to the inner side of the case or closure A, and near its other end in a metallic plate or dial C. The shaft *a* carries at one 35 end a pointer or index *c*, which registers with a series of graduations or marks *d* circularly arranged upon the dial and in the present instance one hundred in number, each representing the value of one cent. Consequently 40 the consecutive numbers of one to one hundred are arranged or marked upon the dial opposite the aforesaid circularly-arranged series of marks *d*. The tooth-wheel has the same number of teeth or notches as the number 45 of graduations or marks on the dial—one hundred—and is engaged by a lever D and a pawl D', the pawl proper D' being pivoted in one end of the lever or bar portion D, which in turn is pivoted at one end in one 50 corner of the casing or closure A upon the rear side of the dial or plate C, and held by a

spring D². This pawl is held in engagement with the ratchet or wheel B by means of a spring *e*, suitably secured upon the back of the casing.

55

The lever D and the pawl D' is kept from lateral displacement by a guide or stout wire *f*, suitably secured in place and arranged with that end in view. *g* is a spring-pressed holding-pawl, also suitably secured to the 60 dial-back and taking into the notches between the teeth of the ratchet or wheel B to prevent its return or reverse movement.

E E' E² E³ E⁴ are keys, which are proportionately graduated or increased in length, 65 and having the inner ends of their shanks engaging the bar or lever D of the lever-pawl, the said shanks passing through and guided in apertures in one side of the closure or case A.

F is an elongated slot in the dial, in which is disposed a slide G, carrying a series of lateral or horizontal pins or projections *g'*—say five—and a pointer or index *g²* registering at certain intervals with consecutive figures on 75 the dial-face, as at *h*, indicating dollars. These pins are engaged by a shoulder *i* upon the inner side of the pointer or index *c*, said shoulder facing inward.

The slot E is of greater length than the 80 slide G, to permit of the required movement of the latter.

It will be seen that when any one of the keys—as, for instance, key E—is moved or pressed inward an intermittent rotation will 85 be imparted to the wheel or ratchet B, which will move or carry the pointer or index *c* forward to the next mark or graduation of the dial C, the pointer or index thus traversing the entire face of the dial when the key has 90 been sufficiently actuated to produce a complete rotation of the wheel or ratchet B. This will indicate and register the fact that one hundred stamps have been disposed of. Simultaneously with the pointer or index *c* registering with the number one hundred (100) the shoulder *i* will engage one of the pins or projections *g'* of the slide G and move it forward, causing its pointer or index *g²* to register with the dollar marking, and indicate 100 that one dollar's worth of stamps has been sold. This operation can be repeated with-

out resetting the slide G until the pointer or index c has engaged all of the pins g' , when the slide G will have moved to or registered with the marking "\$5," indicating that five dollars' worth of stamps have been disposed of. In order to reset the device, the slide G is moved toward the opposite end of the slot and the pointer or index c moved to the number or graduation "100," the slide G then being moved forward to cause its pointer or index g^2 to stand opposite the nought-mark, as at j. The further movement of the pointer or index c will carry the pointer or index g^2 to the one-dollar mark. The aforesaid registration or actuation of the key E is resorted to, of course, in selling single one-cent stamps one at a time. In disposing of greater amounts, or a number of stamps at a time, the other keys are actuated, the particular ones used being governed according to circumstances, two, three, five, and ten cents' worth of stamps being registered by the keys E', E², E³, and E⁴, respectively, they being proportionately graduated or increased in length to accordingly actuate the wheel.

Having described this invention, what we claim, and desire to secure by Letters Patent, is—

1. The combination, with the graduated or numbered plate or dial, having the slide provided with a pin or projection and an index or pointer, of the pointer or index carried by a ratchet or tooth-wheel and having upon one side a shoulder engaging said pin or projection and a series of keys of proportionately increased or graduated lengths, a lever acted

upon by said keys, and a pawl engaging said ratchet or tooth-wheel, substantially as set forth.

2. The combination, with the graduation or numbered plate or dial having the slide provided with a series of pins or projections arranged to project through a slot in said dial, which slot is of greater length than said slide, and a pointer or index, of the index or pointer carried by a ratchet or tooth-wheel and having a shoulder successively engaging said pins or projections of the slide, the graduated keys, and mechanism for the actuation of said ratchet or wheel through said keys, substantially as set forth.

3. The combination of the graduated plate or dial, the slide arranged in a slot in said dial and carrying a series of pins or projections arranged to project through a slot in said dial, which slot is of greater length than said slide, and a pointer or index, the ratchet or tooth-wheel actuated by a lever-pawl and carrying an index or pointer having a shoulder successively engaging the pins of said slide, and the series of graduated keys of proportionately increased or graduated lengths and acting upon said lever and pawl, substantially as set forth.

In testimony whereof we affix our signatures in presence of two witnesses.

WARREN ALLISEN CROCKETT.
JUDSON NOELL HATCHER.
